INVENTOR

Attorney

UNITED STATES PATENT OFFICE.

FRANK M. NICHOLSON, OF HUNT'S, NEW YORK.

BAG-HOLDER.

SPECIFICATION forming part of Letters Patent No. 352,835, dated November 16, 1886.

Application filed June 24, 1886. Serial No. 206,139. (No model.)

To all whom it may concern:

Be it known that I, FRANK M. NICHOLSON, a citizen of the United States of America, residing at Hunt's, in the county of Livingston 5 and State of New York, have invented certain new and useful Improvements in Bag-Holders; and I do hereby declare the following to be a full, clear, and exact description of the invention, such as will enable others skilled in the 10 art to which it appertains to make and use the same, reference being had to the accompanying drawing, and to letters or figures of reference marked thereon, which form a part of this specification.

15 My invention relates to certain new and useful improvements in bag-holders, the object of the same being to provide a cheap and effective means for holding bags so that they can be readily filled with grain, the device being 20 constructed so that the bag can be readily attached and detached therefrom.

In the accompanying drawing, which illustrates my invention, the figure is a perspective view of a bag-holder constructed in accordance with my improvement.

25 A and A' represent converging side frames, which consist of bars *a a*, which are rigidly braced to each other by cross-bars *a'*. The upper ends of the bars *a a* are beveled or rounded on their inner sides, as shown at *b*, and to the opposite sides of the uprights *a a* curved metallic bars or pins *c c* are attached, said bars or hooks being adapted to engage with the upper edge of the bag, so as to hold 35 the same in position, with the upper end open, so that said bag can be filled.

30 B refer to pivoted bars, which are attached to the side pieces, *aa*, of the frame A' by means of bolts, the opposite ends of these bars B B being provided with perforations *d d*, which engage with bolts attached to the frame A, said bolts passing through the perforations in the bars, and being held upon the same by means of thumb-screws. By providing the 40 bars B with adjusting means the distance between the upper ends of the frames can be adjusted so as to suit bags of different sizes.

45 C refers to a bar, which is pivotally attached to one of the side bars of the frame A', the

outer end of the same having curved slots or 50 recesses *e* in the under side thereof, which are adapted to engage with the projecting pin *e'*. This bar is employed for increasing and diminishing the distance between the upper 55 ends of the frames, and also for changing the angle of the side bars, so that the height between the upper ends of the frames and the floor may be varied and suit different lengths of bags.

D refers to a hook, which is pivotally attached to the bar C, and is adapted to engage with perforations *f*, in one of the side pieces of the frame A', so as to steady or hold rigid the supports.

The bag to be filled is placed between the 65 frames A and A' and the bars B B, the upper edge of said bag being placed over the hooks *c c*, the upper bars B being first adjusted in accordance to the width of the bag. After the bag has been filled with grain the distance between the hooks *c c* can be diminished by releasing the bar C after first detaching the hook D, thus placing the frame in a position whereby the bag can be readily removed from the hooks.

70 The device hereinbefore described is cheap in construction, and when not in use the parts can be folded upon each other, so as to occupy but little space.

75 I claim—

A bag-holder comprising the converging side frames, A and A', provided at their upper ends with pins *c c*, the frame A also having the pin *e'* and the frame A' the perforations *f*, the bars B B, pivotally attached to one of 85 the side frames and adjustably attached to the other, a bar, C, provided with recesses *e*, adapted to engage with the projecting pin *e'*, and the pivoted hook D, attached to the bar C and adapted to engage with the perforations 90 *f*, substantially as described, and for the purpose set forth.

In testimony whereof I affix my signature in presence of two witnesses.

FRANK M. NICHOLSON.
